(57) **CLAIM**

The ornamental design for a fire poker, as shown and described.

DESCRIPTION

FIG. 1 is a perspective view of a fire poker.

FIG. 2 is another perspective view of the fire poker of FIG. 1.

FIG. 3 is another perspective view of the fire poker of FIG. 1.

FIG. 4 is another perspective view of the fire poker of FIG. 1.

FIG. 5 is a right side elevational view of the fire poker of FIG. 1.

FIG. 6 is a left side elevational view of the fire poker of FIG. 1.

FIG. 7 is a front elevational view of the fire poker of FIG. 1.

FIG. 8 is a back elevational view of the fire poker of FIG. 1.

FIG. 9 is a top plan view of the fire poker of FIG. 1.

FIG. 10 is a bottom plan view of the fire poker of FIG. 1.

FIG. 11 is a perspective view of the head of the fire poker of FIG. 1.

FIG. 12 is another perspective view of the head of the fire poker of FIG. 1.

FIG. 13 is a right side elevational view of the head of the fire poker of FIG. 1.

FIG. 14 is a left side elevational view of the head of the fire poker of FIG. 1.

FIG. 15 is a front elevational view of the head of the fire poker of FIG. 1.

FIG. 16 is a back elevational view of the head of the fire poker of FIG. 1.

FIG. 17 is a top plan view of the head of the fire poker of FIG. 1; and,

FIG. 18 is a bottom plan view of the head of the fire poker of FIG. 1.

The broken line boundary in FIGS. 11 through 18 forms no part of the claimed design.

1 Claim, 14 Drawing Sheets
